UNITED STATES PATENT OFFICE.

ALONZO G. VAN NOSTRAND, OF BOSTON, MASSACHUSETTS.

DESIGN FOR A POST FOR FAUCETS.

49,199.

Specification for Design.

Patented June 13, 1916.

Application filed January 29, 1916. Serial No. 75,178. Term of patent 14 years.

To all whom it may concern:

Be it known that I, ALONZO G. VAN NOSTRAND, a citizen of the United States, residing at No. 482 Beacon street, Boston, Massachusetts, in the county of Suffolk and State of Massachusetts, have invented a new, original, and ornamental Design for Posts for Faucets, of which the following is a specification, reference being had to the accompanying drawing, forming part thereof.

The figure is an elevational view of the

ornamental post for a faucet as it appears when seen from the front. When seen from the side or the rear the appearance of the post is the same.

I claim:

The ornamental design for a post for faucets, as shown and described.

ALONZO G. VAN NOSTRAND.
